UNITED STATES PATENT OFFICE.

THOMAS MORCOM, OF NORWOOD, OHIO.

WHIFFLETREE-HOOK.

No. 921,267.

Specification of Letters Patent.

Patented May 11, 1909.

Application filed July 24, 1908. Serial No. 445,105.

To all whom it may concern:

Be it known that I, THOMAS MORCOM, a citizen of the United States, and a resident of Norwood, in the county of Hamilton and 5 State of Ohio, have invented a new and Improved Whiffletree-Hook, of which the following is a full, clear, and exact description.

This invention relates to whiffletree hooks, and more particularly such as are provided 10 with resilient retaining means for securing the end of a trace in position on a whiffletree, swingle-tree, or the like. It constitutes an improvement on the device shown and described in my United States Patent No. 15 887,685, dated May 12, 1908.

The object of the invention is to provide a device of the class described, simple in construction and inexpensive to manufacture, which includes a ferrule having a bifurcated 20 end and adapted to be arranged at the end of a whiffletree, swingle-tree or the like, a tongue pivotally carried by the bifurcated end of the head, and a resilient keeper having an upwardly disposed split hook, 25 adapted to engage one end of the tongue to lock a trace end in position, and to obviate the danger of the latter coming off accidentally. The ferrules may be made to fit sword end and other forms of whiffletrees.

30 Reference is to be had to the accompanying drawings forming a part of this specification, in which similar characters of reference indicate corresponding parts in all the views.

Figure 1 is a perspective view of an embodiment of my invention, showing the same in position on a whiffletree, and showing the end of a trace held in place thereby; Fig. 2 is a longitudinal section of the device, showing the tongue in engagement with the retainer; 40 Fig. 3 is a side elevation having a part in section, and showing the tongue released from the retainer; and Fig. 4 is an end view of the device.

In the specific form shown in the drawings, 45 I provide a ferrule 1 adapted to be arranged on one of the ends of a swingle-tree, whiffletree, or the like, and having a constricted end or projection 2. The latter is bifurcated, so that a substantially U-shaped recess 3 is 50 formed in the projection. The base 4 of the recess 3 is under-cut, or beveled, as shown most clearly in Figs. 2 and 3. Pivots arranged between the jaws 5, which form the sides of the recess 3, is a tongue 6. The latter is comprised of a body 7 having lateral extensions 8 and having a substantially rec-

tangular head 9. The extensions 8 have registering openings 10, which, in turn, register with similar openings 11 in the jaws 5. Extending through the openings 10 and 11 is 60 a pivot pin 12, which serves movably to hold the tongue in position. The lower end 13 of the tongue 6 is beveled so that when the tongue is moved into a horizontal position in longitudinal alignment with the projection 2 65 of the ferrule, the lower end will seat against the under-cut portion 4 of the recess 3 to hold the tongue against further downward movement, as shown most clearly in Fig. 3. I further provide a resilient retainer 13 having a 70 portion 14 upwardly disposed. The retainer is removably secured by means of screws 17, in a recess 15 formed by extensions 16 of the ferrule. The screws 17 extend through the ferrule and serve to hold the latter in place 75 upon the whiffletree. The upwardly disposed portion 14 of the retainer has its end bifurcated so that jaws 18 are formed. These jaws are turned back upon themselves to form hooks, adapted to rest against the head 80 9 of the tongue when the latter has been moved into a vertical position and the body has been received in the bifurcated portion of the retainer, as shown most clearly in Figs. 1 and 2.

85

In the operation of the device, the tongue is moved into longitudinal alignment with the constricted end of the head. While in this position, the trace may easily be passed over the tongue until it engages the constricted projection 2. The tongue is then moved into a vertical position, and the upwardly disposed portion 14 of the retainer compressed so that the body 7 of the tongue can pass between the jaws 18. When the tongue is in position, the retainer is released, and secures the tongue, the jaws resting against the outer face of the head 9, thus serving the double purpose of locking the trace on the head by means of the tongue, 90 and of giving further support to the tongue so that the latter cannot be broken or disengaged.

Having thus described my invention, I claim as new and desire to secure by Letters 105 Patent:—

1. In a device of the class described, a ferrule having a constricted, bifurcated end, a tongue pivotally carried at the bifurcated end of said ferrule, said tongue having a head, 110 and a resilient retainer arranged upon said ferrule, said retainer having the free end

thereof bifurcated and upwardly disposed, whereby when said tongue is received in the bifurcated portion of said retainer, the upwardly disposed portion engages at the outer 5 side of the head of said tongue to lock the latter in position.

2. In a device of the class described, a ferrule having a bifurcated end, a tongue pivoted within the bifurcation, a resilient retainer arranged upon the ferrule, and having the free end thereof bifurcated to receive the

tongue therein, the free ends of the bifurcation being upwardly disposed, and the tongue being provided with a head for engagement by the bifurcations. 15

In testimony whereof I have signed my name to this specification in the presence of two subscribing witnesses.

THOMAS MORCOM.
